UNITED STATES PATENT OFFICE.

ANTHONY VANDERVELD, OF GRAND RAPIDS, MICHIGAN.

MEANS FOR CONNECTING SECTIONAL FURNITURE.

1,250,110.

Specification of Letters Patent. Patented Dec. 11, 1917.

Application filed January 8, 1915. Serial No. 1,190.

To all whom it may concern:

Be it known that I, ANTHONY VANDERVELD, a citizen of the United States of America, residing at Grand Rapids, in the county of Kent and State of Michigan, have invented certain new and useful Improvements in Means for Connecting Sectional Furniture; and I do hereby declare the following to be a full, clear, and exact description of the invention, such as will enable others skilled in the art to which it appertains to make and use the same.

This invention relates to a means for connecting sectional furniture with the vertical sectional units disposed in spaced apart relation and for covering the space between the various sectional units in such manner that there will be produced the appearance and the structural effect of a solid built construction. The invention has for its object and purpose the provision of a new and improved means for detachably yet securely fastening the sectional units together and for detachably connecting, at the front and between the spaced apart ends of the sections, a finishing post or pilaster which is normally held tightly in engagement with the sectional units but which may be readily removed upon application of sufficient force. To these and other ends not specifically enumerated I have devised the constructions disclosed in the accompanying drawings, in which;

Figure 1 shows in perspective a plurality of sections connected together and presenting the appearance of a solid construction.

Fig. 2 is a horizontal sectional view taken through the construction illustrated in Fig. 1.

Fig. 3 is an enlarged sectional view of a fragment of the construction taken at the forward ends of spaced apart adjacent sections.

Fig. 4 is a view similar to Fig. 3 but illustrating a slight modification in structure; and

Fig. 5 is a fragmentary side elevation of the construction shown in Fig. 4.

Like reference characters refer to like parts throughout the several views of the drawings.

In the construction of the sectional furniture as shown a plurality of sections 1 are positioned one above the other to any de-

sired height to form an independent vertical multiple sectional unit, said sectional unit being completed by a base 2 on which the lowermost section rests, and by a top of cornice 3 of suitable design resting upon the uppermost section of the sectional unit. A plurality of these vertical multiple sectional units are placed in horizontal relation end to end with adjacent ends spaced a distance apart so that each sectional unit is practically independent of the others and may be taken apart, built up, rearranged and interchanged as desired without disturbing any of the other sectional units of the series. Each section at each end thereof may have connected thereto, as shown in Figs. 4 and 5, a strip 4 located a short distance back of the front edges of the ends of the section, which when the sections are placed end to end, are adapted to contact with each other receiving therethrough a screw 5 which is also inserted through one section end 6 then through the strips 4 and into the adjacent end 6 of the adjacent section, firmly tying the sections together against longitudinal displacement. It however, is apparent that the screw 5 may be removed at will and the sections readily detached.

As thus constructed there will remain a space in front of the strips 4 which I have covered with the facing post 7 of a width such that its edges will extend over and bear against the front edges of the ends 6 of the section. A plurality of spring members 8 are secured to the post 7 on its rear side having spaced apart spring arms terminating in the curved ends 9 which are adapted to seat in grooves 10 formed vertically in the ends 6 of the sections. Said arms have the normal tendency to spring away from each other and bear with a considerable degree of force against the ends of the sections and normally serving to draw the finishing post 7 in tight engagement with the front edges of the ends of the sections. It will be apparent, however, that by the application of sufficient force this post 7 may be readily removed and that it can be as readily replaced when desired.

The strips 4 which, as it has been stated, are secured at each end of the section 6, may, if desired, be formed as indicated in Fig. 2,

that is the strips may be formed as an integral member and not attached to the ends of the sections serving merely as a spacing bar between the ends of the sectional units at a 5 short distance back of the forward edges thereof, in which case bar 4 may reach from the bottom to the top of the sectional units, the same as the finishing post 7.

In Figs. 4 and 5 a modification in structural detail is shown, spring members 11 of the formation shown best in Fig. 5 being secured to the back of the post 7 and having their lower ends adapted to be received back of similar spring members 12 secured to 15 one of the strips 4, the post 7 being applied by placing it against the sections a distance above this normal position and then forcing it downwardly, the springs 11 thereupon passing back of the springs 12 as 20 will be readily understood.

With this construction sectional furniture is provided which may be readily taken apart at any time, each vertical multiple sectional unit being rendered independent 25 of the others upon removal of the finishing post 7 and of the connecting screws 5. Various slight modifications other than those described may be resorted to without departing from the invention which includes 30 all modifications falling properly within the scope of the appended claims.

I claim:-

1. In combination, a series of sections placed in superposed relation to form a multiple vertical sectional unit, a plurality of said sectional units positioned in horizontal relation with adjacent ends spaced apart, vertical spacing strips located between the said units a distance back of the fronts 40 thereof, means for detachably connecting the adjacent ends of the sections of the sectional units together, and a covering post positioned at the front of and between the spaced apart ends of the sections and detachably connected therewith.

2. In combination, a plurality of multiple vertical sectional units located in horizontal alinement with adjacent ends spaced a short distance apart, vertical strips connected to the ends of the sections of each sectional unit, said strips on the adjacent ends of the sections lying against each other, detachable means inserted through said strips and into the section ends for detachably connecting the sections together, and a covering post positioned at the front of and between the spaced apart ends of the sectional units and detachably connected therewith.

3. In combination, a plurality of multiple vertical sectional units located in horizontal alinement with adjacent ends spaced a short distance apart, vertical strips connected to the ends of the sections of each 65 sectional unit, said strips on the adjacent

ends of the sections lying against each other, means passing through the strips detachably connecting the sections together against horizontal displacement, a post positioned at the front of and between the spaced apart ends of the sections, said post having connected therewith a plurality of spring elements, and means engaging said spring elements to yieldingly hold the post in position and draw it tightly against the 75 section, substantially as described.

4. In combination, a plurality of multiple vertical sectional units located in horizontal alinement, means spacing the ends of the units a short distance apart, means detachably connecting the sections of the units and the spacing means together, a post, a plurality of spring elements connected to the post on the rear side thereof, said spring elements extending into the space between the sectional units, and means engaging with said spring elements to detachably retain them and the attached post in position with the post covering the space at the front of and between the sections, substantially as described.

5. In combination, a plurality of multiple vertical sectional units located in horizontal alinement with adjacent ends spaced a short distance apart, vertical strips connected to the ends of the sections of each sectional unit a short distance back of the front of each section, the strips on the adjacent ends of the sections contacting with each other, screws inserted through an end of one section and the strips and into the adjacent end of the adjacent section, a part positioned at the front of and between the spaced apart ends of the sections, said part having connected therewith a plurality of 105 spring elements and means detachably engaged by said spring elements to yieldingly hold the part in position and draw it tightly against the front edges of the sections.

6. In combination, a series of sections placed in superposed relation to form a multiple vertical sectional unit, a plurality of said sectional units positioned in horizontal relation with adjacent ends spaced apart, superposed sectional spacing members interposed between the adjacent ends of sections of said units and disposed vertically along the ends of the respective superposed sections thereof, means connecting said members and adjacent sections together, and a pilaster having a length equal to the height of said sectional units positioned in front of said spacing members and removably connected thereto, substantially as described.

7. In combination, a series of sections placed in superposed relation to form a multiple vertical sectional unit, a plurality of said sectional units positioned in horizontal relation with adjacent ends spaced apart,

spacing members interposed between the adjacent ends of sections of said units, a pilaster located at the front of and between adjacent ends of sections, and detachable interengaging spring members on both the spacing members and pilaster for detachably securing the pilaster in place.

In testimony whereof I affix my signature in presence of two witnesses.

ANTHONY VANDERVELD.
